UNITED STATES PATENT OFFICE.

ALEXANDER K. SUTHERLAND, OF NEW BRITAIN, CONNECTICUT, ASSIGNEE TO THE TRUMBULL ELECTRIC MANUFACTURING COMPANY, OF PLAINVILLE, CONNECTICUT, A CORPORATION OF CONNECTICUT.

QUICK-BREAK SWITCH.

1,271,520.

Specification of Letters Patent.

Patented July 2, 1918.

Application filed November 5, 1917. Serial No. 200,236.

To all whom it may concern:

Be it known that I, ALEXANDER K. SUTHERLAND, a subject of the King of Great Britain, residing at New Britain, Connecticut, have invented a new and useful Quick-Break Switch, of which the following is a specification.

The invention relates to switches of the "quick break" type, and aims to simplify 10 and improve switches of this general character.

Other objects are to produce a switch structure which can be easily assembled, which will be quick and positive in its action and which will be of sturdy construction throughout.

In brief, the invention comprises pivoted switch blades and a cranked operating member therefor, said operating member being 20 connected to the free ends of the switch blades through the instrumentality of a special bracket having a slot receiving the operating crank to form a lost motion connection, and having a lug with which is engaged 25 one end of a throwing spring, whose opposite end is connected with the operating crank.

Another feature of the invention is a special construction of operating member comprising a handle having a hub journaled in the 30 wall of the box which is usually provided to inclose the switch, and a rod anchored in the hub at the inside of the box and provided with an angularly extending 35 arm engaging in the slot and forming the operating crank described.

Other features will appear as the specification proceeds.

In the drawings accompanying the specification, I have illustrated my invention embodied in a practical concrete form, but it will be understood that the invention is susceptible of various modifications without departure from the true spirit and scope 45 thereof.

Figure 1 is a plan view of the switch as mounted in the switch box, the cover of the box being open to expose the switch and the switch being shown in the open circuit position.

Fig. 2 is a side view of the switch box in closed position and the switch in the closed circuit position.

Figs. 3 and 4 are enlarged sectional views taken substantially on the plane of the line 55 3—4 of Fig. 1 to illustrate the operation of the switch throwing spring.

The switch illustrated is of the three-blade type embodying three parallel switch blades 5 pivoted at one end, at 6, on posts 7, and 60 engaging at their free ends with the switch contacts or clips 8. The free end portions of the switch blades are connected in the usual way by a cross bar 9 of insulating material, and the parts thus far described are 65 mounted on a base 10 of suitable insulating material.

The quick break mechanism comprises a bracket 11 mounted on the insulating cross bar 9 provided with an upstanding lug 12 70 having an angularly extending slot 13 therein to receive the arm 14 of a suitable operating member, and a coil spring 15 which is connected between the operating arm 14 and a dependent anchorage lug 16 on the 75 bracket.

The operating member, in the inclosed type of switch illustrated, comprises a handle 17 having a hub 18 journaled in the side wall of the switch housing or casing 19 substantially in line with the switch pivot 6, and the arm 14 which is connected with said hub by means of the angularly bent portion 20 which is seated in an opening provided therefor in the inner end portion of the hub. 85 This operating arm 14 may be formed from ordinary rod stock of the proper length bent to provide the supporting portion 20 for engagement in the hub of the handle.

In the case of three-bladed switches, such 90 as illustrated, it may be desirable to duplicate the bracket constructions to thereby provide connections with the movable switch element at points between the switch blades.

In Fig. 3 the switch is shown in the closed 95 circuit position, the handle 17 having been rocked forwardly, as indicated in Fig. 2, so as to cause the operating arm 14, by engagement with the wall at the forward end of the slot 13, to force the switch blades into 100

firm engagement with the switch contacts. When the switch is to be opened, the handle 17 is swung in the reverse direction or toward the left in Fig. 2. This causes the operating arm 14 to traverse the full length of the angularly disposed slot 13 until it brings up against the wall at the rearward end of said slot whereupon a positive connection is provided between the operating mechanism and the movable switch element. The movable switch element then moves with the operating arm until a point is reached where the friction of the switch clips or contacts 8 is insufficient to hold the switch blades against the tension of the spring or springs 15, whereupon said springs snap the switch blades up out of contact with the switch clips, the lost motion connection between the brackets and the operating arm allowing for this snapping movement. Fig. 4 illustrates the tensioning of the springs preparatory to the snapping of the switch to "off" position.

The brackets 11 may be secured to the cross bar by any suitable means such as the bolts or screws 21, the brackets being ordinarily shaped to fit the cross bar. In the illustration the cross bar is angular in cross section and the bracket is made with a flat base portion seating on top of the cross bar, a dependent side portion 22 extending down across the rear side of the cross bar and terminating in the spring anchorage lug 16 and the upstanding slotted lug 12 is struck up at one end of the flat base portion of the bracket. In this way the bracket may be made from a single piece of sheet metal and may be mounted by simply placing it on the cross bar and applying the securing screw thereto. It is then only necessary to connect the throwing spring between the anchorage lug 16 and the operating arm 14.

The cover 23 of the box, in the case of the inclosed switch, is suitably secured, in the present instance, by means of a spring pressed latch 24 engaging a shoulder 25 on the dependent flange of the cover, said latch being automatically withdrawn when the switch is opened by means of a retracting lever 26 having an angular end portion 27 disposed in a position to be engaged by the part 20 as the handle is thrown to open the switch (see Fig. 1).

My invention, it will be seen, provides a very simple and relatively inexpensive means for transforming an ordinary switch structure into a quick break switch and the device is entirely practical in every respect.

I claim:

1. In a quick break switch, a switch blade pivotally supported at one end, a switch contact frictionally engaged by the opposite free end of the switch blade, a bracket mounted on the free end portion of the switch blade and insulated therefrom, said bracket

having a dependent spring anchorage and an upstanding lug slotted in the general direction of the switch opening movement, a switch operating member working in said slot, and a spring connected between said operating member and the spring anchorage on the bracket.

2. In a quick break switch, parallel switch blades pivotally supported at one end, an insulating cross bar connecting the free ends of said switch blades, switch contacts frictionally engaged by the free end portions of the switch blades, a bracket on the insulating cross bar having a spring anchorage and an upstanding slotted lug, an operating member working in the slot in said upstanding lug and a spring connection between said operating member and the spring anchorage of the bracket.

3. In a quick break switch, substantially parallel switch blades pivotally supported at one end, an insulating cross bar connecting the free ends of said switch blades, switch contacts frictionally engaged by the free end portions of the switch blades, a bracket secured on the insulating cross bar between the switch blades having a dependent spring anchorage and an upstanding lug provided with a slot extending rearwardly toward the plane of the switch pivot, an operating shaft journaled substantially concentric to the switch blade pivot and provided with a cranked portion working in the slot aforesaid, and a switch snapping spring connected between the spring anchorage of the bracket and said cranked portion of the operating shaft.

4. In a switch of the character described, a switch box, an external operating handle having a hub portion journaled in one wall of the box and extending through said wall into the interior of the box, a rod having one end seated in said internally disposed hub portion of the handle and bent angularly to extend from the plane of said wall inward into the body of the box, a switch mounted in said box and comprising pivoted switch blades and switch contacts frictionally engaged thereby the pivotal axis of said switch blades being substantially concentric to the pivoted hub of the operating handle, a lost motion connection between the inwardly projecting portion of the rod and the free ends of the switch blades, and a spring connection between said inwardly extended portion of the rod and said switch blades.

5. In a switch of the character described, a switch box, an external operating handle having a hub portion journaled in one wall of the box and extending through said wall into the interior of the box, a rod having one end seated in said internally disposed hub portion of the handle and bent angularly to extend from the plane of said wall inward into the body of the box, a switch mounted

in said box and comprising pivoted switch blades and switch contacts frictionally engaged thereby, the pivotal axis of said switch blades being substantially concentric to the pivoted hub of the operating handle, a bracket secured to the free swinging end of the switch blades having a dependent spring

anchorage lug and an upstanding lug slotted to receive the inwardly extending portion of the bent rod and a spring connected 10 between said portion of the rod and the spring anchorage lug aforesaid.

ALEXANDER K. SUTHERLAND.
